UNITED STATES PATENT OFFICE.

THOMAS J. WINANS, OF BINGHAMTON, NEW YORK.

DISCHARGING-VALVE ADAPTED TO AIR-GUNS.

SPECIFICATION forming part of Letters Patent No. 495,767, dated April 18, 1893.

Application filed October 24, 1889. Serial No. 328,003. (No model.)

To all whom it may concern:

Be it known that I, THOMAS J. WINANS, of Binghamton, county of Broome, State of New York, have invented a new and useful Improvement in Discharging-Valves Especially Adapted for Air-Guns, of which the following is a true and exact description, reference being had to the accompanying drawings, which form a part of this specification.

- 10 My invention relates especially to the discharging valve of guns using compressed air as a motive power, and my object is to provide a valve which will be moved by the force of the compressed air and which, in my preferred construction, will admit the compressed air to the gun barrel in gradually increasing quantity so that the projectile will not be subjected to the full amount of pressure until after it has moved some distance in the gun 15 barrel, the pressure increasing in regulated quantity as the projectile moves forward. This mode of admitting the air behind the projectile is of advantage with all sorts of air guns, but more especially where the projectile 20 is a shell charged with a high explosive as by avoiding shock, the danger of explosion in the gun is greatly diminished.

My discharging valve while as already stated is especially adapted to air guns may be advantageously used in any mechanism where it is important that a fluid should open the valve by its own pressure or where a regulated gradual opening of the discharge valve is desired.

35 My invention will be best understood after a description of the drawings in which it is illustrated as applied to an air gun and the novel features of my device are hereinafter clearly pointed out in the claims.

40 Reference being now had to the drawings,— Figure 1, is an elevation of my improved firing valve taken on a central longitudinal section; Fig. 2, a cross-section on the line $x-x$ of Fig. 1; Fig. 3, a cross-section on the line $y-y$ of Fig. 1; and Fig. 4, a view similar to that of Fig. 1 with the valve rod and movable valve removed.

A is the gun barrel, and B the valve casing, the barrel and casing being secured together 45 in any convenient manner, as by a screw thread C; and an annular projection A', extending into the chamber B' of the valve cas-

ing and having a perforation or preferably a number of perforations, a , arranged obliquely thereon as shown in the drawings. The valve 55 casing is divided into two chambers B' and B³, by means of the partition B²; the chambers being connected by the perforation I I', passing through the partition B², and preferably having a valve seat i arranged in it as 60 shown. The area of this perforation is variable and can be adjusted at will by means of the set screw J having a needle valve J' on its lower end.

D is the valve rod and upon its interior 65 end is screwed the valve F fitting into the annular projection A'. Upon the same valve rod is secured the valve G G' fitting tightly in the valve chamber B'; and a third valve, H, is secured on the rod D so as to move in 70 and close the chamber B³.

In the plan shown a link E is pivoted to the outer end e of the rod B and to the end e' of the bent lever E', which said bent lever is pivoted at b^2 to a projecting arm b of the 75 valve casing B. The levers E and E' form a toggle joint, and a block b' , is provided for the knuckle to rest upon. b^3 is an opening into the valve chamber B' adapted to be connected with the reservoirs of compressed air 80 (not shown). The portion of the chambers B' and B³ between the valves and the partition B² is filled with a fluid, preferably oil.

The operation of my improved device is as follows: The valve being in the position 85 shown in Fig. 1, and the portion of chamber B' between the valve G G' and the admission ports a being charged with compressed air, or connected with a reservoir for compressed air, the valves are held stationary by means of a 90 stop of any convenient kind acting on the end of the valve rod D. As shown, the toggle levers E E' serve as a stop when their knuckle, e' , rests on the block b' . As soon as the stop is removed, as by throwing the knuckle e' up 95 by pulling on the end of the bent lever E', the pressure of the compressed air acting on the greater area of valve G G', causes the said valve to move backward; the valves F and H being attached to the same valve rod 100 have of course a corresponding motion, and as the valve F moves backward in the annular projection A', it uncovers the admission ports or perforations a gradually, first

one, then two, and so on, so that the compressed air is admitted to the gun barrel A in gradually increasing quantity. To prevent the ports *a* from being opened too rapidly, I have devised the combination of the valve G G' and H with the perforated partition wall B². It is of course evident that when the spaces between these valves and the partition wall is filled with oil or other fluid, the oil must pass through the perforation in the partition to enable the valve G G' to move backward and by means of the needle valve J', I am able to regulate the area of the perforation so as to offer any desired resistance to the passage of the oil through it and thus regulate the motion of the valve G G' and of the valve F connected with it, with the utmost nicety.

The construction shown by which the valves G G' and F are both secured upon the same valve rod, is one of great simplicity, but I do not wish to be understood as limiting my invention to this special detail of construction except in those claims in which it is expressly made an element; and of course the oblique arrangement of the firing ports *a*, while of value in regulating the gradual admission of the air to the gun barrel, are not absolutely essential, the regulated motion of a valve over a firing port of any outline resulting in the same graduated admission of the air which is the chief point of advantage sought by my invention.

The combination of the discharge valve F with the valve G G' of greater area so as to virtually make up a differential valve is of prime importance as by it the movement of the discharge valve is effected by the compressed air itself and this feature of my invention may be used with advantage apart from the valve H. Of course the relative area of valves F and G G' may be varied at will; for the purpose of illustration the difference is exaggerated in the drawings. The special construction of the discharge orifices and the valve F is not in my broader claims a matter of importance so long as the valve F is of less area than the valve G G' to which it is attached and which with it forms a differential valve which will open with the pressure of the fluid in the chamber B'.

Having now described my invention, what I claim as new, and desire to secure by Letters Patent, is—

55 1. In combination with a valve chamber adapted to contain fluid under pressure and having a contracted passage at one end with discharge ports formed in it; a piston valve moving in said contracted passage to control the ports; and a valve of larger area than the end of the piston valve connected with it to form a differential valve, and closing the other end of said chamber all substantially as specified and so that the pressure of the fluid in the valve chamber will act to open the valve.

2. In combination with the valve chamber

B' adapted to contain fluid under pressure and having a discharge port at one end, the valve chamber B³ separated from chamber B' by the perforated partition B², the valve F controlling the discharge port in chamber B', the valve G G' of larger area than valve F situated in chamber B' and connected with valve F so as to form a differential valve; the valve H situated in chamber B³ and connected with valve G G' and an adjusting valve arranged to control the passage through partition B², all substantially as and for the purpose specified. 75

3. In combination with the valve chamber B', adapted to contain fluid under pressure, the annular projection A' having a discharge port or ports formed in it; the chamber B³ separated from chamber B' by a perforated partition B², the valve F moving in projection A', the valve G G' of larger area than valve F moving in chamber B', the valve H moving in chamber B³, and the connecting rod D uniting said valve, all substantially as and for the purpose specified. 85

4. In combination with the valve chamber B', adapted to contain fluid under pressure, the annular projection A' having one or more obliquely-set discharge ports *a* formed in it; the chamber B³ separated from chamber B' by a perforated partition B², the valve F moving in projection A', the valve G G' of larger area than valve F moving in chamber B', the valve H moving in chamber B³, and the connecting rod D uniting said valve, all substantially as and for the purpose specified. 95

5. In combination with the valve chamber B', adapted to contain fluid under pressure, the annular projection A' having a discharge port or ports formed in it; the chamber B³ separated from chamber B' by a perforated partition B², the valve F moving in projection A', the valve G G' of larger area than valve F moving in chamber B', the valve H moving in chamber B³, the regulating valve J' arranged to control the orifice in partition B², and the connecting rod D uniting said valve, all substantially as and for the purpose specified. 105

6. In combination with the valve chamber B', adapted to contain fluid under pressure, the annular projection A' having a discharge port or ports formed in it, the chamber B³ separated from chamber B' by a perforated partition B², the valve F moving in projection A', the valve G G' of larger area than valve F moving in chamber B', the valve H moving in chamber B³, the connecting rod D uniting said valves, and the toggle jointed levers E E' secured to rod D and arranged to serve at a stop therefor, all substantially as and for the purpose specified. 115
